DESIGN FOR A LIGHTING FIXTURE

Louis J. Coneglia, Cleveland, Ohio

Application December 6, 1946, Serial No. 135,307

Term of patent 7 years

(Cl. D48—4)

To all whom it may concern:

Be it known that I, Louis J. Coneglia, a citizen of the United States, residing in the city of Cleveland, county of Cuyahoga, and State of Ohio, have invented a new, original, and ornamental Design for a Lighting Fixture, of which the following is a specification, reference being had to the accompanying drawing, forming a part thereof.

Figure 1 is a side elevation of the lighting fixture, showing my new design.

Figure 2 is a plan view thereof, and

Figure 3 is an end view thereof.

I claim:

The ornamental design for a lighting fixture, substantially as shown.

LOUIS J. CONEGLIO.
